DESIGN FOR A BOOK END

Edward S. Lynch, New York, N. Y.

Application September 10, 1938, Serial No. 79,829

Term of patent 7 years

To all whom it may concern:

Be it known that I, Edward S. Lynch, a citizen of the United States of America and a resident of the Borough of Manhattan, city, county, and State of New York, have invented a new, original, and ornamental Design for a Book End, of which the following is a specification, reference being had to the accompanying drawing, forming a part thereof, in which

Fig. 1 is a front elevational view of a book end showing my new design;

Fig. 2 is a side elevational view thereof; and

Fig. 3 is a top plan view thereof.

I claim:

The ornamental design for a book end, as shown.

EDWARD S. LYNCH.
